Primary Examiner — Cathron Brooks

Assistant Examiner — Daniel J Domino

(74) Attorney, Agent, or Firm — Banner & Witcoff, Ltd.

(57) **CLAIM**

The ornamental design for a display screen with graphical user interface, as shown and described.

DESCRIPTION

The sole FIGURE is a front view of a display screen with graphical user interface showing the new design.

The broken line showing of the text, display screen and the device are for environmental purposes only and form no part of the claimed design.
